CHINA CABINET OR THE LIKE

Ernest Herrmann, Hillsdale, N. J., assignor to Heywood-Wakefield Company, Gardner, Mass., a corporation of Massachusetts

Application March 14, 1955, Serial No. 35,041

Term of patent 7 years

(Cl. D33—19)

Fig. 1 is a front perspective view of a china cabinet showing my new design,

Fig. 2 is a top plan view thereof partially in cross section along the line 2—2 of Fig. 1,

Fig. 3 is a cross sectional view on the line 3—3 of Fig. 1, and

Fig. 4 is an enlarged fragmentary elevational view illustrating the detail of one of the door elements.

I claim:

The ornamental design for a china cabinet or the like, substantially as shown.
